United States Patent

Des. 241,128
Patented Aug. 24, 1976

241,128

LOCOMOTIVE

James R. Chapin, Erie, Pa., assignor to General
Electric Company, Erie, Pa.

Filed Dec. 20, 1974, Ser. No. 534,595

Term of patent 14 years

Int. Cl. D12—03

U.S. Cl. D12—38

Fig. 2

FIG. 1 is a perspective view of a locomotive showing my new design illustrating either the left front side or the right rear side;

FIG. 2 is a perspective view illustrating either the left rear side or the right front side thereof;

FIG. 3 is a perspective view of the interior thereof looking toward the front, with the sliding windows on the right side in open position; and

FIG. 4 is a perspective view of the interior thereof looking toward the rear.

I claim:

The ornamental design for a locomotive, as shown and described.
